COMBINED CRASH PAD AND TRAY

Arthur Rich, Flushing, N. Y.

Application January 18, 1956, Serial No. 39,837

Term of patent 14 years

(Cl. D14—6)

FIG. 1.

FIG. 2.

FIG. 3.

Fig. 1 is a perspective view of a combined crash pad and tray embodying my new design, the portions shown in broken lines being for convenience of illustration only;

Fig. 2 is a top view of my combined crash pad and tray; and

Fig. 3 is a right-side view of my combined crash pad and tray.

I claim:

The ornamental design for a combined crash pad and tray, as shown and described.
